UNITED STATES PATENT OFFICE.

FRANK A. LUNDQUIST, OF CHICAGO, ILLINOIS.

SELECTING DEVICE FOR TELEPHONE-EXCHANGES.

No. 871,092.

Specification of Letters Patent.

Patented Nov. 12, 1907.

Original application filed August 8, 1903, Serial No. 168,694. Divided and this application filed January 16, 1905.
Serial No. 241,247.

To all whom it may concern:

Be it known that I, FRANK A. LUNDQUIST, a citizen of the United States of America, and a resident of Chicago, county of Cook, and State of Illinois, have invented certain new and useful Improvements in Selecting Devices for Telephone-Exchanges, of which the following is a specification.

My invention relates to telephone exchanges and more particularly to the calling devices used at the local stations of an automatic exchange.

It has for its object the simplification of the process by which a subscriber at any one station can easily and quickly make connections to any one of a large number of other stations.

15 In the accompanying drawings Figure 1 is a front elevation of the telephone box of a local station; Fig. 2 is a view of the interior of the box showing part of the electric circuits; Fig. 3 is an enlarged view of part of the mechanism on the front cover of the telephone 20 box, the upper portion being removed; Fig. 4 is a section on line 4—4 of Figs. 2 and 3; and Fig. 5 is a diagram of the electric circuits for one telephone and the switching mechanism associated therewith.

On the front of the telephone box 82 is a pointer 83 which is movable by a hand over the numbered dial 25 84. The pointer 83 is mounted on a spindle 85, on the inner part of which is a spring 86, a gear 87, a ratchet wheel 88, a hook 89, and a lever 38. The spring 86 turns the spindle 85 so as to hold the handle to the 30 pointer 83 normally against a stop pin 110. Another stop pin 111 prevents the pointer being moved too far. The ratchet wheel 88 is secured to the spindle 85, but the gear 87 is loose and is provided with a pawl 112 which engages the teeth of the ratchet wheel. When 35 the pointer 83 is moved by hand, the ratchet wheel 85 turns under the pawl 112, but when released the spring 86 causes the ratchet wheel to drive the gear 87. The gear 87 is connected by a train of gearing to the spindle 113, to the inner end of which is secured a mutilated 40 contact disk 13 and a disk of insulation 114. Also secured on the spindle 113 is a lever 115 to which are pivoted two weights 116 which partially surround, and are adapted to produce frictional contact with, a stationary disk 117. When the pointer 83 has been 45 moved by hand and released, the spring 86 drives the spindle 113 rapidly in the direction of the arrow, but the centrifugal force of the weights 116 causes them to bite on the disk 117 and thus act as a governor to prevent too rapid rotation. Secured to an insulating 50 block 118 is a spring contact 12 which normally bears against the insulation 114, but once during each rotation of the spindle 113 comes into electrical contact with the mutilated disk 13. When in normal position the hook 89 engages a pin 119 on one of the weights 116 to 55 stop them and prevent their momentum from throw-

ing a strain upon the gearing. In normal position the lever 38 has one end bearing against a contact point 37 and the other end against a U-shaped or forked lever 14. Adjacent to one arm of the lever 14 is a contact 25, and to the other arm is a contact strip 15. Normally the lever 38 holds the lever 14 away from the contact 25 and into electrical connection with the contact 15. The contact pieces 13, 14 and 38 are all in electrical connection with the base or plate 120, so that an electrical connection to one is free to pass to 60 either of the others. The rest of the contact devices at the telephone are all insulated.

When the pointer 83 has been moved by hand and released, the spring 86 will move the pointer towards zero, and the parts on the inside of the cover, in the 65 directions of the arrows of Fig. 2. The movement of the pointer by hand moves the parts secured to spindle 85, but not those secured to spindle 113. As the movement by hand moves the lever 38 in a direction opposite to the arrow, it will be evident that it will 70 release pin 119, break the electrical connection to contact 37, and will release the lever 14 so that spring 130 (Fig. 4) will move it so as to break the connection to contact 15 and make it to contact 25. These parts are so related to each other that a movement of the pointer 75 83 to the point 0 on the dial 84, will move the ratchet wheel 88 one tooth, and a release of the pointer 83 will give the spindle 113 one rotation so as to produce one contact between 12 and 13, which contact will occur after the connection is broken between 14 and 25 and 80 85 made between 14 and 15. If the pointer 83 is moved to "1" on the dial 84, the disk 13 will be given two rotations and make two contacts with 12, during one of which 14 is in contact with 25, and during the other of which 14 is in contact with 15. If moved to "2" 90 on the dial, there will be two contacts between 12 and 13 while 14 is in contact with 25 and one while in contact with 15. It will therefore be apparent that, as 95 13 and 14 are on a common base, the lever 14 acts as a switch to throw the last contact of any series made between 12 and 13 from one line to another. Also that the figure or number on the dial 84 to which the pointer 83 is moved, represents the number of contacts made between 12 and 13 before the switch 14 throws the connection from the line represented by contact 25 to that 100 105 represented by contact 15.

The receiver hook H, when rising in the ordinary manner, connects to a lever 49, and when descending, first moves 49 so as to make electrical connections between 47, 48, 49 and H, and then releases 49 so as to 110 break these connections. Briefly, the pin on the hook H engages the rear edge of the lever 49, and, as the hook descends, the pin pushes the lever forward on its pivot until the pin clears the lower edge of the lever when the lever falls back to its original position.

When the hook rises the pin passes under the lever 49 by bending it outward. Also at the telephone are the customary receiver R, induction coil E, transmitter T, battery Y, generator G, ringer F, and certain contact devices which will be apparent from the description of the electric circuits.

The switching mechanism which is associated with the devices so far described is illustrated diagrammatically in the upper part of Fig. 5. Briefly, it consists 10 of a pointer P which is moved over a series of contact points K by means of a ratchet wheel O and a magnet A. It also has a platform 62 which is swung on a pivot 61 by means of a magnet B. There is also a ratchet bar 68 which is moved axially on the platform 62 by a 15 magnet C. The bar 68 carries some contact makers 73 which are used to make electrical connections with contact points 76 and hence with the telephones of other stations. There are also a releasing magnet D and certain connections and contacts associated with 20 the switching mechanism, the object of which will become apparent in the description of the circuits.

The switching mechanism does not form a part of the present application and is shown here diagrammatically only for the purpose of illustrating the circuits 25 over which impulses are sent by the calling device.

Assuming that a subscriber wishes to call telephone "No. 345" the operation would be as follows:—He removes his receiver R when the hook H rises to make contacts with 20 and 125. He then moves his pointer 83, 30 which, upon release, runs back to a point just beyond "0" on the dial 84. Moving the pointer 83 breaks the connection between 14 and 15, which connection is not reestablished until just before the pointer reaches its normal position. In running back to normal position the disk 13 makes a series of contacts with the spring 12. Except for the last one, these contacts are without effect, because all connections are open at some point; consequently for the first movement of the pointer 83 the distance of this movement is immaterial. At the last contact between 12 and 13 the current flows from battery X—10—11—12—13—base—14—15—16—17—18—19—20—H—21—22—23—A—24—50—100—102—X. This circuit I call "circuit A" because it passes through the magnet A, and a current flowing through "circuit A" causes the pointer P to be moved one step in the direction of the arrow. The first time the current flows through A after removing the receiver R, the pointer P is moved into connection to line 31. On a second movement of the pointer 83, each 45 successive contact between 12 and 13 (except the last) sends a current from X—10—11—12—13—base, 14—25—26—27—28—29—30—P—31—B—50—100—102—X. This is called "circuit B" and acts to swing the platform 62 so as to bring the pointers 73 to successive points 76 in 50 arcs described from the pivot 61. The last contact reproduces a current through "circuit A" and moves the pointer P to the next contact K. A third movement of the pointer 83 will result the same as the second, except that the pointer P, being on a different contact 55 point K, the current will flow through magnet C instead of magnet B. This would be through "circuit C." The final contact in this case also reproduces a current through magnet A which moves the pointer P to the next contact point K and puts it into connection with the selected point 76 on the first table 75. It

will be noticed that in "circuit A" the current flows from 12 to 18 by way of 13—14—15—16 and 17. On the front of the telephone box is a push button M by which a contact may be made between 18 and 127 so that the current may flow from 12 to 18 by way of 126 70 and 127. It will therefore be apparent that a current can be sent through "circuit A" either by the final contact from moving the pointer 83 or by pushing the button M.

Returning again to the process of making connections to telephone "No. 345" it will be seen that the subscriber removes his receiver and turns the pointer 83 an indefinite (any) distance beyond "0" on the dial 84. This results in moving the pointer P one space. He then turns the pointer 83 to the figure "4" (for the 75 tens) and lets it return to normal position. This results in sending four successive currents over "circuit B" which moves all of the pointers 73 to the radial rows representing the forties on the table 75, and also another current over "circuit A" which moves P to 80 the next contact K. He then turns the pointer 83 to the figure "5" (for the units) and lets it return to normal. This results in five successive currents over "circuit C" and one over "circuit A," which moves the pointers 73 to the points five on the rows of forties, 90 or the points 45 on each table, and also moves the pointer P into connection with the pointer 73 of the first table 75. To shift it to "345" he may either turn the pointer 83 three times to "0" on the dial 84, or preferably push the button M three times. This results in shifting the pointer P to connection with the table of three hundreds. To recapitulate, the subscriber removes his receiver, moves his pointer 83 any distance, then to "4" then to "5", then pushes the button three times. That the time consumed in this 95 operation may be as short as possible; the spring 86 and the governor 116 are so related to each other that the successive contacts will be made as rapidly as it is practical for the magnets A, B, and C to perform their operations. While the telephone connected to in the 100 preceding description is "No. 345", and may be indicated to the subscriber by that number, I prefer to use a different system of numbering that will give the subscriber more precise information as to how the proper connection should be made. For example, the telephone which would actually be No. 345, I would describe to the subscriber as "No. 145—3". The first three figures would indicate the points to which the pointer 83 is successively moved, and the figure after the dash the number of times the button is pushed. 110 Assuming that connections have been made to the proper telephone in the manner described, the subscriber turns the crank of the generator G causing a contact between 34 and 35, when the current flows as follows:—G—34—35—36—37—38—base—14—15—16—17—18—19—20—H—21—22—23—A—24—50—along 120 100 to 50 of the called telephone. The details of this circuit, and of the talking circuit between stations, are given in full in the application from which this is divided, and are not material to the present case.

Hanging up the receiver breaks all connections and returns pointers P and 73 to their normal position in the following manner:—The descent of the hook H makes contacts between 47, 48, 49 and H when a current flows:—X—10—46—47—48—49—H—21—22—23—130

A—24—50—100—102—X. This actuates A and causes 30 to make a contact between 52 and 53 during the time when there is a contact between 47 and 48. This causes a second current to flow:—X—10—46—47—48—

5 51—27—28—52—53—D—54—50—100—102—X. The current through D releases the various parts from their propelling magnets, A, B and C and permits the respective retracting springs to return to their normal positions.

What I claim is:

- 10 1. In a selecting device, a dial provided with numbers on its face, a pointer movable by hand to any position on said dial, means for automatically returning said pointer to its normal position, means for making a series of electrical contacts by the movement of said pointer, two lines or courses over which electrical impulses may be sent, means whereby said electrical contacts will cause as many electrical impulses to be sent over one of said lines as was indicated on the dial by the primary movement of said pointer, and means whereby one additional electrical impulse will be automatically sent over the other line after the impulses have ceased over the first line.
- 15 2. In a selecting device, a numbered dial and a pointer therefor, means whereby said pointer may be moved by hand to any position on said dial and be automatically returned to its normal position, means for automatically
- 20
- 25

sending as many electrical impulses over a given course as are indicated on the dial by the manual movement of said pointer, and means for automatically sending one additional impulse over a different course after the impulses have ceased over the first course.

3. A numbered dial, a pointer adapted to be moved to any position on said dial, automatic devices for returning said pointer to a normal position, means controlled by the movement of said pointer for sending a series of electrical impulses over a given course, a switch, and means for operating said switch by the movement of said pointer so as to send an additional electrical impulse over a second course.

4. The combination with a numbered dial, a pointer and automatic devices for moving said pointer over said dial, 40 of a line over which electrical impulses may be sent by the movement of said pointer, a switch located in said line, a second line adjacent to said switch, and means controlled by the terminal portion of a movement of said pointer whereby said switch is moved so as to transfer an impulse 45 following a series of impulses from the first line to the second line.

Signed at Chicago, Ill, this 13th day of Jan. 1905.

FRANK A. LUNDQUIST.
